RAIL RETAINING AND SPIKE FASTENING
MEANS

George W. Muller, Miami Beach, Fla.

Application April 21, 1944, Serial No. 532,071

12 Claims. (Cl. 238—294)

1

This invention relates to railway track structures, and represents a carrying forward of the inventions described and claimed in my prior patents, No. 2,291,743 of August 4, 1942 and No. 2,434,579 of January 13, 1948, for retaining rails upon tie-plates and for preventing upward loosening movement of the spikes by which the tie-plates are fastened upon the ties, as well as for urging the spikes more firmly into the ties in harmony with any downward wear of the tie-plates into the ties.

Unless tie-plate and rail fastening spikes are held against upward loosening movement and are urged downwardly as wear or sinking of the tie-plates into the ties occurs, they soon become loose, creep upwardly, fail properly to accomplish their purpose and permit the ties to drop from the rails, with the result that an infirm, dangerous and noisy track condition soon develops and becomes worse at a progressively increasing rate with the passing of time. Accordingly, the general object of the present invention is to provide simple, practical and efficient means to maintain railway spikes at all times tight whereby the track structure is maintained firm so as to possess long life and be conducive to smooth, safe passage of trains thereover with little track noise.

In connection with any given tie and tie-plate two spikes may sometimes be employed at either or both sides of a rail, and in such instances both of the spikes at either side of the rail may be employed as combined tie-plate and rail fasteners, or solely as tie-plate fasteners, or one of them may be employed solely as a tie-plate fastener and the other may be employed as a combined tie-plate and rail fastener. In any event, one special object of the present invention is to provide in any such instance a resilient clamp-plate which spans the space between the spikes and is seated upon the heads thereof and which is secured to the tie-plate and is maintained under downward flexure exerting constant downward pressure upon the spikes so that the latter are held effectively against any upward loosening movement relative to the tie and are urged more firmly into the tie as any wear or sinking of the tie-plate into the tie occurs. Thus, the tie-plates are maintained firmly seated upon the ties and the ties are held against dropping relative to the rails so that should any tie tend to become loose in the road-bed the finer particles of the road-bed material may creep beneath and maintain the same high. As a consequence, all of the ties remain high and firmly supported, loose spikes and tie-plates are avoided and the net result is, as

2

aforesaid, a firm track which possesses long life and is conducive to smooth, safe passage of trains thereover with little track noise.

Another special object of the present invention is to provide, for use in association with a clamp-plate which is employed to secure two spikes against upward loosening movement, a resilient rail-retaining plate to retain the rail upon the tie-plate.

10 Another special object of the invention is to provide for use in connection with any single spike, a clamp-plate of novel form for cooperation with the spike and the tie-plate in a novel manner to hold the spike against upward loosening movement relative to the tie.

With the foregoing and other objects in view, which will become more fully apparent as the nature of the invention is better understood, the same consists in the novel combination and arrangement of elements, and in the novel features of construction thereof, as will be hereinafter more fully described, illustrated in the accompanying drawings and defined in the appended claims.

15 25 In the accompanying drawings, wherein like characters of reference denote corresponding parts in related views:

Figure 1 is a transverse section through a portion of a track showing a portion of a tie, a tie-plate superimposed thereon, the base portion of rail seated upon the tie plate, and a pair of clamp-plates constructed and employed in accordance with the invention.

Figure 2 is a plan view of the structure shown in Fig. 1, the rail being shown in section.

Figure 3 is a side elevation of the structure shown in Figs. 1 and 2.

Figure 4 is a view similar to Fig. 1 illustrating an alternative spike and clamp-plate arrangement.

Figure 5 is a plan view of the construction shown in Fig. 4.

Figure 6 is a side elevation of the construction shown in Figs. 4 and 5.

Figure 7 is a view similar to Figs. 1 and 5 illustrating another alternative embodiment of the invention.

Figure 8 is a cross-sectional view of the construction shown in Fig. 7.

50 Figures 9 and 10 are views similar to Fig. 8 illustrating other alternative arrangements in accordance with the invention; and

Figures 11, 12 and 13 are views similar to Figs. 1, 2 and 3, respectively, illustrating another 55 alternative embodiment of the invention.

According to each of the illustrated embodiments of the invention a portion of a tie is designated as A, a tie-plate or a portion thereof superimposed upon the tie is designated as B, the base portion of a rail seated upon the tie-plate is designated as C, spikes for fastening the tie-plate upon the rail and, in some instances serving also for rail retaining purposes, are designated as D, a spike-securing clamp-plate is designated as E, and a fastener for securing the clamp-plate to the tie-plate is designated as F.

According to the specific embodiment of the invention illustrated in Figs. 1 to 3, a pair of spikes D is employed at each side of the rail, one spike of each pair being spaced outwardly from the related edge of the rail flange 10 and serving solely as a tie-plate fastener and the other being located adjacent to the related edge of the rail flange and having the lip portion of its head 11 overlying the rail flange to serve as a rail retainer. The heads of the tie-plate-fastening spikes are shown as being directly engaged with the tie-plate to hold the latter against upward movement relative to the tie. On the other hand, the lips of the rail-retaining spikes are shown as being spaced above the rail flanges to avoid interference with free passage through the rail of the natural vertical wave motion imparted thereto by trains passing thereover. Moreover, the tie-plate is shown as being provided with shoulders 12 for cooperation with the edges of the rail flanges to hold the rail against lateral movement relative to the tie-plate. It is to be understood, however, that the lips of the rail-retaining spikes may engage the rail flanges, as shown for example in Fig. 9, and that said rail-retaining spikes may be employed in lieu of tie-plate shoulders to hold the rail against lateral movement relative to the rail. In any event, the shanks 13 of the spikes extend through openings in the tie-plate into the tie and the space between the heads 11 of the spikes of each pair is spanned by a clamp-plate E, the end portions 14 of which are seated upon said heads 11. Moreover, the clamp-plates are resilient, being formed preferably from high grade spring steel, and each of them, intermediate its ends, is suitably secured to the tie-plate and is maintained under downward flexure as, for example, by means of a fastener F in the form of a bolt 15. The weight of the rail itself and train weights imposed upon the rail tend constantly to urge the tie-plate downwardly against the tie. Accordingly, since each clamp-plate is secured to the tie-plate and is constrained to move downwardly therewith, the end portions of each clamp-plate are caused to exert constant downward pressure upon the heads of the related pair of spikes whereby any upward loosening movement of the spikes relative to the tie is prevented and the same are forced more firmly into the tie as any sinking or wearing of the tie-plate into the tie occurs. As a consequence, the spikes are maintained tight and the tie-plate is maintained securely fastened upon the tie. Moreover, the tie is held against dropping relative to the rail so that in the event any space should tend to develop between the underside of the tie and the roadbed, the finer particles of the roadbed material may creep into such space and thus maintain the tie high and firmly supported. Accordingly, in any given length of track all of the spikes and the tie-plates are maintained tight and the ties are maintained high and firmly supported so that they firmly support the rails. The net result is a firm track structure which possesses long life

and which is conducive to smooth, safe passage of trains thereover with little track noise.

In a construction as shown in Figs. 1 to 3 the heads of the rail-retaining spikes are disposed 5 higher than the heads of the tie-plate securing spikes. Accordingly, the outer end portions 14 of the clamp-plates E are stepped downwardly relative to the intermediate portions 16 of said plates and are connected to said intermediate portions by substantially vertically disposed leg portions 17 to compensate for this difference in the elevations of said spike heads. If desired, however, the intermediate and the outer end portions of said clamp-plates may be disposed in substantially 15 a common plane, or both outer end portions of said clamp-plate may be stepped downwardly relative to the intermediate portion thereof, in any instance where this might be desirable. Moreover, both end portions 14 preferably are 20 formed to provide downwardly opening socket formations of substantially spherical contour to accommodate and seat securely upon the rounded tops of the spike heads and to insure against rotation of the clamp-plates about their fasteners F from their operative positions relative to the spikes.

Regarding the fasteners F, these may be in the form of bolts as shown, or they may be of any other suitable form such, for example, as shown in my prior patent or in my copending application.

According to the embodiment of the invention illustrated in Figs. 4 to 6, both of the spikes shown are solely tie-plate fasteners. In other respects 35 the construction is the same as the Figs. 1 to 3 construction, except that both end portions 14 of the clamp-plate are stepped downwardly relative to the intermediate portion 16 of said plate in view of the heads of the spikes D being disposed at the same elevation.

According to the Figs. 7 and 8 embodiment of the invention the construction is the same as illustrated in Figs. 4 to 6 with the addition of a 40 separate rail-retaining plate E' the outer end portion 18 of which overlies and is held against the medial portion 16 of the clamp-plate E by the fastener F and the inner end portion 19 of which is seated upon the rail flange. If desired the plate E' may be welded or otherwise fastened to the plate E.

The plate E' is resilient and acts resiliently to 45 retain the rail upon the tie-plate without seriously interfering with passage through the rail of the natural vertical wave motion imparted to it by trains passing over the same. Said plate also 50 serves to hold the rail from creeping, tilting or twisting.

To hold the plate E' against rotation about the fastener F from its operative position relative to the rail and the clamp-plate E, said plate E' may 55 have at its outer end a down-turned flange 20 engaged with the outer edge of the medial portion 16 of the clamp-plate E, and, if desired, said flange may extend downwardly to and seat upon the top of the tie-plate to act as a stop to limit downward flexure of the plate E by the fastener F, thus to predetermine the amount of spring energy stored in said plate E. Alternatively, any other suitable means may be provided for holding the plate E' against rotation and for limiting 60 downward flexure of the plate E.

Fig. 10 illustrates that, in a construction otherwise the same as, or the equivalent of, the Figs. 7 and 8 construction, the rail retaining plate, 65 designated as E², may have a downwardly

directed portion 21 adjacent to its inner end to seat upon the tie-plate adjacent to the rail flange, as upon the rib 12 for example, and may have its inner end portion overlying the rail flange in spaced relationship thereto to retain the rail upon the tie-plate and yet permit the rail to partake freely of the natural vertical wave motion imparted to it by trains passing thereover.

In some instances a pair of spikes or only a single spike may be employed at either or both sides of the rail for both rail and tie-plate fastening purposes to the exclusion of any spike or spikes for solely tie-plate fastening purposes. An instance of this kind is illustrated by way of example in Fig. 9 of the drawings wherein the spike D has the lip of its head 11 overlying and engaging the rail flange so as to serve as both a rail and tie-plate fastener and there is not employed any spike spaced outwardly from the rail solely for tie-plate fastening purposes. In any such instance the lip or lips of the spike head or heads, as the case may be, may engage the rail flange or may be spaced thereabove, and one or more clamp-plates of the type illustrated in Fig. 9 may be employed to hold the spike or spikes against upward loosening movement and to urge the same downwardly more firmly into the tie as any wear or sinking of the tie-plate into the tie takes place.

The inner end portion 14 of the clamp-plate illustrated in Fig. 9 and designated as E³ is provided with a downwardly opening socket formation of preferably spherical contour to accommodate the spike head and the outer end portion of said clamp-plate is provided with a downwardly directed leg 22 to rest upon the tie-plate, while between its inner and its outer ends said clamp-plate is secured to the tie-plate and maintained under suitable downward flexure by a suitable fastener F. Consequently, said clamp-plate acts in the same general manner as the clamp-plates previously described to urge the spike constantly downwardly and thus hold the same against any upward loosening movement relative to the tie; also, to urge the spike more firmly into the tie in harmony with any wear or sinking of the tie-plate into the tie.

Figs. 11, 12 and 13 illustrate a tie-plate which is fastened to a tie by a single spike at each end of the tie-plate, and further illustrate clamp-plates similar to the clamp-plate shown in Fig. 9, one individual to each spike, for securing the spikes against upward loosening movement relative to the tie. As distinguished from the Fig. 9 construction, the spikes of the Figs. 11 to 13 construction are solely tie-plate-fastening spikes and the spike-head-engaging end portions of the clamp-plates, designated as E⁴, are stepped downwardly relative to the medial portions of said clamp-plates as in the form of the invention illustrated in Figs. 4 to 6 of the drawing and as indicated at 17', while the other ends of said clamp-plates are turned downwardly for engagement with the tie-plate as in the Fig. 9 construction and as indicated at 22'. In other respects the Figs. 11 to 13 construction is the same as the Fig. 9 construction and the mode of operation is as heretofore described in connection with the other forms of the invention. Of course, there may be more than a single spike at each end of the tie-plate, in which event duplicates of the holding devices illustrated in Figs. 11 to

13 may be provided for the additional spike or spikes.

According to any of the different embodiments of the invention the fastener F may be located at any desired point along the length of the medial portion of the clamp-plate so that the two end portions of the clamp-plate may be urged downwardly under either equal or unequal forces as may be desired.

From the foregoing description considered in connection with the accompanying drawings, it is believed that the construction and operation of the present spike holding means will be clearly understood and its advantages appreciated. It is desired to point out, however, that while only certain specific structural embodiments of the invention have been illustrated and described, the same is readily capable of specifically different structural embodiments within its spirit and scope as defined in the appended claims.

I claim:

1. In a railway track structure, a tie, a tie-plate superimposed thereon, a rail seated upon said tie-plate and acting by its own weight and by train-weights imposed thereon to urge the tie-plate downwardly against the tie, a pair of headed track - element - fastening - spikes extending through openings in said tie-plate into the tie, a highly resilient sheet steel clamp-plate spanning the space between said spikes and seated upon the heads thereof, and a bolt securing said clamp-plate intermediate its ends to said tie-plate and maintaining the same under material downward flexure exerting constant downward pressure upon said spikes, whereby the latter are held against upward loosening movement relative to the tie and are urged constantly downwardly into more secure engagement with the tie in harmony with any appreciable amount of downward wear of the tie-plate into the tie.

2. In a railway track structure, a tie, a tie-plate superimposed thereon, a rail seated upon said tie-plate and acting by its own weight and by train-weights imposed thereon to urge the tie-plate downwardly against the tie, a pair of headed tie-plate-fastening-spikes extending through openings in said tie-plate into the tie, a highly resilient sheet steel clamp-plate having its end portions seated upon the heads of said spikes, a highly resilient sheet steel rail-retaining plate having its outer end portion superimposed upon the medial portion of said clamp-plate and its inner end portion overlying the flange of the rail, and a bolt engaged with said tie plate and extending through the outer end portion of said rail-retaining plate and through the medial portion of said clamp-plate and holding said outer end portion of said rail-retaining plate against the medial portion of said clamp-plate and maintaining the said medial portion of said clamp-plate under material downward flexure, whereby said spikes are held against upward loosening movement relative to the tie and are urged constantly downwardly into more secure engagement with the tie in harmony with any appreciable amount of downward movement of the tie-plate relative to the tie, and whereby said rail-retaining plate is maintained in operative relationship to the rail.

3. A railway track structure as set forth in claim 2 including means separate from and co-operating with the bolt to hold the rail-retaining plate in fixed relationship to the clamp-plate.

4. A railway track structure as set forth in claim 2 in which the rail-retaining plate has a

lip engaging an edge of the clamp-plate and cooperating with the bolt to hold the rail-retaining plate in fixed angular relationship to the clamp-plate.

5. A railway track structure as set forth in claim 2 in which the inner end portion of the rail-retaining plate is seated upon the rail flange.

6. A railway track structure as set forth in claim 2 in which the rail-retaining plate is provided at its outer end with a downwardly extending flange seated upon the tie-plate.

7. A railway track structure as set forth in claim 2 in which the rail-retaining plate is provided at its outer end with a downwardly extending flange engaging an edge of the clamp-plate and cooperating with the bolt to hold the rail-retaining plate in fixed angular relationship to the clamp-plate and in which said flange is seated upon the tie-plate.

8. A railway track structure as set forth in claim 2 in which the rail-retaining plate adjacent to its inner end is seated upon the tie-plate adjacent to the outer edge of the rail flange and in which the inner end portion of said rail-retaining plate overlies the rail flange in spaced relationship thereto.

9. A railway track structure as set forth in claim 2 in which the end portions of the clamp-plate are disposed below the medial portion of said plate and are connected with the said medial portion of said clamp plate by substantially vertically disposed leg portions.

10. A one-piece highly resilient sheet steel clamp plate to hold a pair of spikes against upward loosening movement relative to a tie into which they are driven, said clamp plate comprising end portions to be seated upon the heads of the spikes and a medial portion to be fastened under material downward flexure to a tie plate, and a second highly resilient sheet steel rail holding clamp plate to have one end portion seated upon and fastened against the intermediate portion of said spike holding clamp plate and to have its other end portion overlie the flange of a rail.

11. A one-piece highly resilient sheet steel clamp plate to hold a pair of spikes against up-

ward loosening movement relative to a tie into which they are driven, said clamp plate comprising end portions to be seated upon the heads of the spikes and a medial portion to be bolted to a tie plate and drawn under material downward flexure to maintain said end portions urged downwardly against the spikes, and a second highly resilient sheet steel clamp plate to have one end portion seated upon and fastened against the medial portion of said first mentioned plate and to have its other end portion overlie the flange of a rail, the first mentioned end portion of said second mentioned plate being turned downwardly to engage the outer edge of the medial portion of said first mentioned plate to hold said second mentioned plate against rotation relative to said first mentioned plate.

12. Clamp plates as set forth in claim 11 in which the downturned end portion of the second mentioned plate is of a height to contact a tie plate when the medial portion of the first mentioned plate is under downward flexure.
